UNITED STATES PATENT OFFICE.

JAMES T. BARBER, OF BROOKLYN, NEW YORK.

ENGINE-STARTING MECHANISM.

No. 874,153.

Specification of Letters Patent.

Patented Dec. 17, 1907.

Application filed June 8, 1907. Serial No. 377,998.

To all whom it may concern:

Be it known that I, JAMES T. BARBER, citizen of the United States, residing at Brooklyn, in the county of Kings and State of New York, have invented certain new and useful Improvements in Engine-Starting Mechanisms, of which the following is a specification.

This invention contemplates certain new and useful improvements in starting mechanism for engines or motors, and relates particularly to that type of mechanism which is designed to automatically uncouple the starting crank from the engine, or motor shaft, in case a reverse impulse is imparted to the shaft by a premature explosion during the operating of "cranking", the invention being especially applicable for use in connection with explosive engines of automobiles, motor boats and the like.

10 The invention has for its object a simple, durable and efficient construction of mechanism for automatically releasing the crank from the engine shaft in case of "back firing", and the invention consists in certain constructions, arrangements and combinations of the parts which I shall hereinafter fully describe and then point out the novel features in the appended claims.

For a full understanding of the invention 30 and the merits thereof and also to acquire a knowledge of the details of construction of the means for effecting the result, reference is to be had to the following description and accompanying drawings, in which:

35 Figure 1 is an elevation, partially in section, parts being locked in position, of my invention; Fig. 2 is a view similar to Fig. 1, but showing the clutch members separated; and, Fig. 3 is a detail view of the pawl and its connections.

Corresponding and like parts are referred to in the following description and indicated in all the views of the drawings by the same reference characters.

40 Referring to the drawing, the numeral 1 designates the crank shaft of an explosive or internal combustion engine, 2 the relatively fixed clutch member which, in the present instance, is shown provided with a ratchet face, and 3 designates the relatively movable clutch member which is formed with a complementary ratchet face and which is mounted on the revoluble starting element which, in the present instance comprises a shaft section 4 journaled in any suitable bearings (not shown), and a starting crank 4^a provided with

the usual handle, as shown. A spring 5 is interposed between the clutch members 2 and 3 and tends to force said members apart. The teeth of the ratchet clutch members 2 and 3 are beveled, so that after the operation of starting the engine has been effected, the shaft may continue to run without the starting element participating in such movement.

45 A ratchet disk 6 is secured to the engine framework or some other stationary part, being provided for this purpose, in the present instance, with apertured ears 6^a, and the engine shaft 1 passes freely through said disk, as clearly illustrated in the drawings. A complementary ratchet disk 7 is mounted to revolve freely on a sleeve around the crank clutch member 3, and is normally pressed into engagement with the clutch disk 6 by means of a coil spring 8. Formed on or 50 movable with the ratchet disk 7 and projecting from the outer face thereof is a toothed wheel 9. A spring pressed pawl 10 is adapted to travel ahead over the teeth of the wheel 9 in the direction in which the starting crank 4^a is turned to start the engine, said pawl 10 being pivotally mounted on a disk 11, the hub of which is mounted on the shaft portion 4 of the starting element, being secured thereto by a set screw 12 or similar means. 55 In the practical operation, the pawl 10 will travel ahead over the teeth of the wheel 9, permitting the engine to be cranked, but if the engine should "back fire", it is obvious that the pawl 10 would engage the teeth of the wheel 9, thereby causing the ratchet disk 7 to be turned reversely and backed off of the stationary ratchet disk 6, thereby forcing the clutches 2 and 3 apart after a slight, but immaterial reverse movement of the starting element, so as to promptly release such element from the engine shaft and permit the engine to run backwardly without swinging the starting crank around. Hence, it will be seen that all danger of injuring the operator 60 is avoided by my invention, and that I have provided a very simple, durable and efficient construction of device for this purpose.

Having thus described the invention, what is claimed as new is:

65 1. The combination of an engine shaft provided with a relatively fixed clutch member, a starting element provided with a relatively movable clutch member complementary to the fixed clutch member and adapted to engage the same, a relatively fixed ratchet disk 110 encircling said shaft, a relatively movable

- and loose ratchet disk encircling the relatively movable clutch member and adapted to engage the relatively fixed ratchet disk, a toothed wheel movable with the relatively 5 movable ratchet disk, a pawl mounted to travel ahead over the teeth of said wheel and designed to engage therewith upon a reverse movement, and a support for said pawl secured to the starting element.
- 10 2. The combination of an engine shaft, provided with a relatively fixed clutch member, a starting element provided with a relatively movable clutch member adapted to engage the fixed clutch member, a spring 15 tending to separate the clutch members, a stationary ratchet disk encircling the shaft, a relatively movable ratchet disk adapted to engage the stationary ratchet disk and encircling the relatively movable clutch mem-
- ber, said movable clutch disk being provided 20 with an outwardly projecting toothed wheel, a spring tending to force the movable ratchet disk into engagement with the stationary ratchet disk, a pivoted spring pressed pawl mounted to travel freely over the teeth of 25 said wheel in one direction and to engage said teeth upon movement in the opposite direction, and a disk upon which said pawl is mounted, said disk being secured to the starting element, as and for the purpose set forth.

In testimony whereof I affix my signature in presence of two witnesses.

JAMES T. BARBER. [L. S.]
